UNITED STATES PATENT OFFICE.

LEWIS FERRY MOODY, OF PHILADELPHIA, PENNSYLVANIA.

HYDRAULIC TURBINE.

1,341,859.

Specification of Letters Patent.

Patented June 1, 1920.

Application filed May 28, 1919. Serial No. 300,412.

To all whom it may concern:

Be it known that I, LEWIS F. MOODY, a citizen of the United States, residing at Philadelphia, in the county of Philadelphia and State of Pennsylvania, have invented certain new and useful Improvements in Hydraulic Turbines, of which the following is a specification.

The principal object of my invention is to provide a new and advantageous construction for the stay vanes and associated structure in the casing or entrance conduit of a hydraulic turbine. In the accompanying drawings, I have illustrated two specific embodiments of the invention. After these have been considered, I will point out some of the advantages of my invention and what may be accomplished by practice thereunder. I now proceed to describe the two particular embodiments shown in the drawings. It will be understood that modifications may be made within the scope of the invention.

Referring to the drawings, Figure 1 is a section on the turbine axis and on the line 1—1 of Fig. 2.

Fig. 2 is a horizontal transverse section on the line 2—2 of Fig. 1 to reduced scale;

Fig. 3, showing a modification, is a section containing the axis on the line 3—3 of Fig. 4;

Fig. 4 is a horizontal section approximately on the line 4—4 of Fig. 3;

Fig. 5 is another section containing the axis and taken on the line 5—5 of Fig. 4.

In the drawings, I have followed the practice, somewhat common among turbine draftsmen, of bringing certain elements along their respective circumferences into the plane of an axial section.

Referring to Figs. 1 and 2, the turbine casing is shown with its runner removed from the space 11, above which is the head cover 13, and below is the draft tube section 12. On the section 12 rests the lower distributor plate 15 with bearings for the pintles 16 of the adjustable gates 17 which are on respective shafts 19 controlled from a governor, not shown, by the gate levers 20. The upper distributor plate is designated

as 18.

The supply conduit 21 is of spiral form with its wall 22 in sections fastened together by circumferential flanges 23. The casing 22 is open around its inner side toward the runner between the upper flange 24 and the lower flange 26. The flanges 23 are

strengthened at 25 and 27 as indicated in the drawings.

Between the annular edge portions 24 and 26 of the casing 22 stand the stay vanes 30. Each vane 30 is cast integrally with an upper head or crown 28, an upper lining wall section 29, a lower lining wall section 31 and a lower head or base 32. The crown 28 and the lining wall section 29 are connected by end walls 39 and intermediate ribs 40, and similarly for the base 32 and lining wall section 31. Thus it will be seen that the stay vanes are cast in units with one vane and its crown and base to each unit. These units are assembled, independently of each other, between the flanges 24 and 26 and fastened thereto by the stud bolts 33 and 34. A slight clearance is left between the consecutive heads and bases around the turbine as indicated at 36. Accordingly, the only machine work that has to be done on the stay vane sections (besides drilling and tapping the bolt holes) is to face the horizontal top and bottom fitting surfaces where the heads 28 and 32 are bolted to the flanges 24 and 26.

The modification shown in Figs. 3, 4 and 5 has the inflow conduit formed of reinforced concrete walls. In this case the stay vane sections with their heads are cast integrally, but the heads are more widely spaced apart around the turbine than in the form shown in Figs. 1 and 2. When the concrete walls 22', 24' and 26' are made, the anchor bolts 33' and 34' are embedded therein, and the casing reinforcement is arranged in any suitable manner to coöperate with these anchor bolts so as to transfer the stress from the reinforcement to the stay vanes 30' and the turbine structure. The stay vane sections are positioned by assembling them with the pit liner 43 and draft tube liner 12', and the concrete walls are formed up around them, the concrete filling the spaces between the successive heads 28' and 32' as indicated at 41 in the drawings. The hollow spaces 37 and 38 between the head 28', the wall 29' and the pit liner 43, and between the head 32', the wall 31' and the draft tube liner 12' are also filled up with concrete.

One of the problems in designing the casing in a hydraulic turbine is that of supporting the walls of the casing against the internal pressure of the contained water. Any section containing the axis such as the section of Fig. 1 shows that the casing has

the form of a pipe with one portion of each circumference cut away at the point where the water enters the turbine guide vanes and runner. In order to carry the tension across this space due to the pressure of the water within, it is necessary to supply tie members or stays of some sort. Besides carrying the tension due to the internal water pressure in the casing, these stays must also be capable of acting under certain conditions as compression members or struts to support the weight of the upper portion of the casing and the superposed parts, such as an electric generator. In low head plants as a rule, the stay vanes act mainly as struts. In high head plants, they evidently act as struts when the turbine is idle and the conduits empty of water, but in normal operation or when shut down with the conduits containing water under pressure, the stay vanes are subject to tensile stress. In most installations the stays are likely to be subjected to both kinds of stress in varying degree at different times.

The use of ordinary stay bolts or rods to take care of the stresses just discussed is objectionable, because they offer an obstruction to the flow. Accordingly, it has been common to cast a stay vane ring as a whole or in a small number of large sections. In accordance with this method, when the stay vane ring has been made in sections, these sections have been assembled together by means of bolts to form a complete ring and this has been machined on a large boring mill so as to fit with the casing, head covers, etc. Another way has been to cast the stay vanes integrally with the rest of the casing, but this involves serious risk of leaving initial stresses in the structure by the process of casting and cooling so that the strength of the resultant casting is indeterminate.

My invention, of which examples have been disclosed in the foregoing specification, overcomes the objections to the above mentioned methods of bracing the casing walls. As disclosed in this specification, each vane is cast integrally with a small crown section at one end and a small base section at the other end, but these sections are not intended to be bolted together and a little clearance is left between them so that there is no occasion for machine work between them. The only places that have to be machined are the plane horizontal top and bottom surfaces, which are parallel and can be readily machined without the necessity for assembling the sections in a boring mill, the operation being performed by planing a number of the sections at once on a planer or by other well known methods.

The pressure of the water within the casing not only sets up stresses in the plane of

an axial section tending to spread apart the inner edges of the casing as heretofore discussed but it sets up stresses in a circumferential direction around the axis tending, for instance, to pull apart the casing sections where bolted together as at flanges 23. (Fig. 2.) When the stay vane ring has been integral or in sections bolted together, it has been a part of the casing wall and has been depended upon to meet these last mentioned stresses to a certain extent, and hence when the ring has been in sections it has been necessary to bolt the sections strongly together. This has often been a difficult matter because of the difficulty of getting space for the bolts. By my invention the stay vane sections are not connected and all this circumferential stress is thrown on other elements than the stay vane structure, for instance on the flanges 23, 25, 27, in which there is ample space for the necessary bolts and the difficulty of bolting the stay vane sections together is entirely avoided.

Not only do I avoid the necessity for machine work between the sections by leaving a clearance between them, but I leave a clearance between the base and crown and the adjacent distributor plates, so that the only fitting to be done is on the top and bottom surfaces.

In addition to the facility of the machine work in connection with my invention, the task of casting is much simplified, because instead of casting at one time a large and heavy speed ring or a large section thereof, which requires the use of cores in either case, I cast the single small sections separately, each casting being simple and easy to handle. If any vane should prove to be defective, it can be rejected without involving sacrifice of an entire speed ring or a large speed ring section.

For large turbine units, my invention provides an excellent solution of the problem of shipment; heretofore it has been a problem of much difficulty to ship large speed ring sections. The comparatively small sections of my invention can be readily shipped and handled.

In a turbine having a cast metal casing made in sections, the stay vane sections can be assembled in the shop in the various casting sections and then can be shipped in place in their respective casing sections. In turbines of the concrete casing type the largest piece which requires machining on a boring mill, in the type of turbines now commonly used, is the speed ring. The dimensions of this ring therefore place a limit on the size of the turbine which can be built in a shop equipped with a certain capacity of boring mill. In the design provided by my invention this limitation is removed, and it therefore becomes possible to manufacture tur-

bines of larger size than would otherwise be possible in a shop having limited boring mill capacity.

The design shown in Figs. 3, 4 and 5 would be suitable only for very low heads. In units of this type intended for heads of moderate amount, the stay vane sections would be spaced more closely together, and would frequently be closely spaced with merely enough clearance between them to avoid the necessity for machining the adjacent faces, as in the case of the embodiment shown in Figs. 1 and 2.

I claim:—

- 15 1. In combination in a hydraulic turbine, a circumferential series of stay vanes standing between the casing walls above and below, said series being made in a large number of sections and each section comprising a crown part and a base part and a small number of vanes, each section being held in place in the series by having its crown part and base part respectively fastened to the turbine structure above and below.
- 20 2. In combination in a hydraulic turbine, a circumferential series of stay vanes standing between the casing walls above and below, said series being made in a large number of sections and each section comprising a crown part and a base part and a small number of vanes, each section being held in place in the series by having its crown part and base part respectively fastened to the turbine structure above and below, and said vanes serving as struts to sustain the weight of the upper wall and as tie members to hold said walls against pressure within the casing.
- 25 3. In combination in a hydraulic turbine, a circumferential series of stay vanes standing between the casing walls above and below, said series being made in a large number of sections, and each section consisting of a single casting comprising a crown part and a base part and a small number of vanes, each section being held in place in the series by having its crown part and base part respectively fastened to the turbine structure above and below.
- 30 4. In combination in a hydraulic turbine, a circumferential series of stay vanes standing between the casing walls above and below, said series being made in a large number of sections entirely separated from one another by clearance spaces and each section comprising a crown part and a base part and a small number of vanes, each section being held in place in the series by having its crown part and base part respectively fastened to the turbine structure above and below.
- 35 5. In combination in a hydraulic turbine, a circumferential series of stay vanes standing between the casing walls above and below, said series being made in a large number of sections and each section consisting of a single casting comprising a crown part and a base part and a small number of vanes, said crown and base parts having respectively upper and lower parallel surfaces machine finished and fastened to the turbine structure.

6. In combination in a hydraulic turbine, a circumferential series of stay vanes standing between the casing walls above and below, said series being made in sections, each section comprising a crown part and a base part and a single vane between them, each section being held in place in the series by having its crown part and base part respectively fastened to the turbine structure.

7. In combination in a hydraulic turbine, a circumferential series of stay vanes standing between the casing walls above and below, said series being made in sections, each section consisting of a single casting comprising a crown part and a base part and a single vane between them, each section being held in place in the series by having its crown part and base part respectively fastened to the turbine structure above and below.

8. In combination in a hydraulic turbine, a circumferential series of stay vanes standing between the casing walls above and below, said series being made in sections, each section consisting of a single casting comprising a crown part and a base part and a single vane between them, each section being held in place in the series by having its crown part and base part respectively fastened to the turbine structure above and below.

9. In combination in a hydraulic turbine, a conduit around the runner and opening toward it, and a circumferential series of stay vanes standing across between the walls thereof, said series of vanes being made in a large number of sections with a small number of vanes and a base part and a crown part in each section, said base and crown parts being fastened respectively to the lower and upper inner edges of the conduit wall.

10. In combination in a hydraulic turbine, a conduit around the runner, and a circumferential series of stay vanes standing across between the walls of the conduit and fastened thereto, said series of vanes being made in a large number of sections with a small number of vanes in each section.

11. In combination in a hydraulic turbine, a conduit around the axis adapted for a large component of radial flow and having an upper wall and a lower wall with an opening between them toward the axis, and means to stay the walls at their edges adja-

cent to this opening, said means consisting of a circumferential series of vanes in sections with a small number of vanes in each section and a common base and a common 5 crown for each section, said base and crown for each section being fastened directly to the said edges of the walls.

12. In combination in a hydraulic turbine 10 a series of independent stay vane sections, each having a crown part and base part integral with the vane part but separate from and free of contact with or attachment to the base parts and crown parts of adjacent sections.

13. In combination in a hydraulic turbine 15 a series of independent stay vane sections, said sections each having a crown part and base part separate from and free of contact with or attachment to the base parts and 20 crown parts of adjacent sections.

14. In combination in a hydraulic turbine having an inlet space surrounding the 25 turbine runner, a series of separate stay vane sections connected at both ends to the portion of the turbine structure on either side of said inlet space but free of contact with or attachment to each other.

15. In combination in a hydraulic turbine having an inlet space surrounding the 30 turbine runner a series of separate stay vane sections connected by parallel faced surfaces on both ends to the portions of the turbine structure on either side of said inlet space but free of contact with or attachment to 35 each other.

16. In combination in a hydraulic turbine, a circumferential series of stay vanes standing between the casing walls above and below, said series being made in a large 40 number of sections and each section com-

prising a crown part and a base part and a small number of vanes, each vane being formed to guide the water with a tangential component of motion, each section being held in place in the series by having its 45 crown part and base part respectively fastened to the turbine structure above and below.

17. In combination in a hydraulic turbine, a circumferential series of stay vanes 50 standing between the casing walls above and below, said series being made in a large number of sections and each section comprising a crown part and a base part and a small number of vanes, each vane being 55 oblique to the corresponding radius, each section being held in place in the series by having its crown part and base part respectively fastened to the turbine structure above and below.

18. In combination in a hydraulic turbine, a circumferential series of stay vanes standing between the casing walls above and below, said series being made in a large 60 number of sections and each section comprising a crown part and a base part and a small number of vanes, each section being 65 clear of contact with and of direct attachment to other sections.

19. In combination in a hydraulic turbine, a circumferential series of stay vanes standing between the casing walls above and below, said series being made in a large 70 number of sections and each section comprising a crown part and a base part and a small number of vanes, each section being 75 clear of direct stress communication with other sections.

LEWIS FERRY MOODY.
